William Greyell

UNITED STATES PATENT OFFICE.

WILLIAM GREYELL, OF WOODINVILLE, WASHINGTON.

ECCENTRIC FOR CONTROLLING STEAM VALVES ON STEAM ENGINES.

1,402,597.

Specification of Letters Patent.

Patented Jan. 3, 1922.

Application filed July 26, 1920. Serial No. 398,942.

To all whom it may concern:

Be it known that I, WILLIAM GREYELL, a citizen of the United Kingdom of Great Britain, Dominion of Canada, residing at 5 Woodinville, county of King, State of Washington, have invented a new and useful Eccentric for Controlling Steam Valves on Steam Engines, of which the following is a specification.

10 My invention relates to improvements in the eccentric which controls the steam valve on a steam engine, regulating the admission of steam into the piston chamber and the objects of the improvement are:

- 15 1. To conserve and compound steam.
2. To permit of steam expansion for driving power.
3. To so regulate the admission and cut-off of steam to and from the piston chamber that steam expansion drives the piston from $\frac{1}{4}$ to $\frac{1}{3}$ of its distance.

I attain these objects by the mechanism illustrated in the accompanying drawing in which:

25 Fig. 1 is a diagrammatic view showing the shape of the cam mounted on the driving shaft, which in its revolutions contacts with the wheels mounted in end of the steam valve connecting rod on either side of the driving shaft. The full lines show the neutral position when the steam valve is closed, the dash lines show the position when the valve is emitting steam into the cylinder through the left hand port, and the dotted lines show the position when the steam valve is emitting steam into the cylinder through 30 the right hand port.

35 Fig. 2 is an assembly view showing the yoke at the end of the connecting rod holding the rolls or wheels against the cam which is mounted on the driving shaft of the steam engine, and a cross sectional view of the steam chest and cylinder showing the steam valve in neutral.

40 Figures 3, 4, 5, and 6 are diagrammatic views showing the consecutive positions of the cam and its contacts with the wheels mounted in the end of the connecting rod as it opens and closes the steam valve.

45 Fig. 3 shows the position as the cam opens the left hand port to full width, and Figure 4 shows the position when the cam has closed the left hand port, showing the distance traveled by the piston between the time of opening and closing the left hand 50 port to be from $\frac{1}{4}$ to $\frac{1}{3}$ of the total distance the piston travels.

Figure 5 shows the position as the cam opens the right hand port to full width, and Figure 6 shows the position when the cam has closed the right hand port; again showing the distance traveled by the piston while the steam port is open.

Similar numerals refer to similar parts throughout the several views. 65

Figure 1 shows a diagrammatic view wherein "1" is the main driving shaft. "2" is the cam mounted on "1" as it is in neutral position or such position as when the steam valve is closed. "3" is the same cam in the position it is in when it has by contact with the right hand roller "5" driven it into its position "6" thereby pulling the connecting rod "13" and opening the left hand steam port "14" and admitting steam from the steam chest "15" into the piston cylinder "16." At the same time the left hand roller "8" has advanced to the position "9" and as the cam "2" in its revolution contacts with the left hand roller "8" in its position "9" and drives it to the left and into the position "10" the right hand roller or wheel takes the position "7" and the connecting rod "13" drives the steam valve "17" to the left and opens the right hand steam port "18" admitting steam into the cylinder "16" through "18." The wheels or rollers "5" and "8" are mounted on axles "19" and "20" respectively and remain constantly in contact with the cam in its revolutions, a key 90 in the journal box of "5" being indicated by "21" adjusting the relation of the wheels to the cam "2" so as to keep and maintain the contact. Alongside of the cam "2" and mounted upon the driving shaft "1" is the box "22" upon which the two parts "23" and "24" of the divided connecting rod "13" ride as the rod drives back and forth.

I am aware that prior to my invention eccentrics controlling steam valves and steam slide valves of diverse types have been made. I therefore do not claim such a combination broadly, but I do claim—

A slide valve operating mechanism comprising a drive shaft, a boxing for said shaft, a pair of arms slidable on the boxing, a cam carried by and rotatable with the shaft and a pair of adjustable rollers in constant engagement with said cam for operating a connecting rod attached to the said arms to open and close the inlet and exhaust ports of a steam chest. 105 110

WILLIAM GREYELL.
